CLAIM

The ornamental design for a wash basin with attached shelves, as shown and described.

DESCRIPTION

FIG. 1 is a perspective view of a wash basin with attached shelves showing my new design;

FIG. 2 is a right side elevational view thereof, the left side elevational view being a mirror image;

FIG. 3 is a partial front elevational view thereof wherein the missing section of the right side shelf is a mirror image of the left side shelf shown;

FIG. 4 is a partial rear elevational view thereof wherein the missing right side shelf is a mirror image of the left side shelf shown;

FIG. 5 is a top plan view thereof; and,

FIG. 6 is a bottom plan view thereof.
